UNITED STATES PATENT OFFICE.

EDWARD L. McCCLAIN, OF GREENFIELD, OHIO, ASSIGNOR TO THE AMERICAN PAD & TEXTILE COMPANY, OF GREENFIELD, OHIO, A CORPORATION OF OHIO.

HORSE-PAD HOOK.

No. 892,072.

Specification of Letters Patent.

Patented June 30, 1908.

Application filed July 29, 1907. Serial No. 385,973.

To all whom it may concern:

Be it known that I, EDWARD L. McCCLAIN, a citizen of the United States of America, and resident of Greenfield, county of Highland, State of Ohio, have invented certain new and useful Improvements in Horse-Pad Hooks, of which the following is a specification.

The object of my invention is a horse pad hook wherein the journal bar for the hook is secured to the pad by means which are of a construction which does not become readily weakened by the action of the acid in the sweat of the animal and which is of a form such as to distribute the pressure upon the hook over a comparatively large surface of the pad, to prevent the tearing thereof. This object is attained by the means described in the specification and illustrated in the accompanying drawings, in which,

Figure 1 is a perspective view of a collar pad supplied with a hook embodying my invention. Fig. 2 is a plan view of the hook bar. Fig. 3 is a perspective view of the 25 prong bearing plate used with the bar shown in Fig. 2. Fig. 4 is a sectional view through a pad showing a hook attached to the bar shown in Fig. 2. Fig. 5 is a sectional view taken upon line $x-x$ of Fig. 4. Fig. 6 is a 30 perspective view of another modification.

Referring to Figs. 1—5, the invention is shown as applied to a collar pad, A. The reinforcing plate, or bar, B, has prongs, b , b' , struck up from it and the journal bar, C, has 35 eyelets, c , c' , at its ends. The plate, or bar, B, is placed upon the inner side of the pad and its prongs, b , b' , are pushed through the pad, engage the eyelets, c , c' , and are bent down over the same, as illustrated in Figs. 40 4 and 5. The journal loop, d , of the hook, D, engages the journal bar, C.

In the modification shown in Fig. 6, the

hook, D, is journaled upon a plate, or bar, C², which has a central slot, c^4 , and perforations near its end. The plate, or bar, B², is 45 narrow and is bent at its ends into prongs, b^4 , b^5 . The journal bar, C², is placed upon the exterior of the pad and the bar, B², upon the interior of the pad. The prongs, b^4 , b^5 , are forced through the pad and through the perforations in the bar, or plate, C², and are 50 turned over at the ends, as illustrated in Fig. 6.

In each of these modifications it is seen that the parts are few and of a form which 55 lend themselves readily to manufacture. The bearing surfaces of the plates upon the interior of the pad are extensive, so that the pull of the prongs thereon is distributed over a comparatively large surface of the pad. 60 The prongs being formed integral with one or the other of the plates, they will withstand the chemical action of the sweat of the animal better than separate headed rivets.

What I claim is:

1. The combination of a horse pad, a hook bar upon the outer side of the pad, a hook journaled upon the hook bar, a bar upon the inner side of the pad having two prongs formed integral with it, one at each of its 70 ends, the said prongs extending through the pad and engaging the hook bar.

2. The combination of a horse pad, a hook bar consisting of a plate having a central slot and perforations at its ends, a hook journaled upon the plate by passing through the slot, a bar upon the inner side of the pad having its ends turned into prongs which project through the pad and through the holes in the hook-bar and are bent down upon the same. 80

EDWARD L. McCCLAIN.
